ATTORNEY

UNITED STATES PATENT OFFICE.

WILLIAM S. PETERSEN, OF FORT DODGE, IOWA.

ADJUSTABLE CHECK-WIRE HOLDER.

1,258,360.

Specification of Letters Patent.

Patented Mar. 5, 1918.

Application filed July 18, 1916. Serial No. 109,934.

To all whom it may concern:

Be it known that I, WILLIAM S. PETERSEN, a citizen of the United States, residing at Fort Dodge, in the county of Webster and State of Iowa, have invented certain new and useful Improvements in Adjustable Check-Wire Holders, of which the following is a specification.

This invention relates to a check-wire holder and more particularly to an adjustable holder for a check-wire for use in connection with a corn planter.

The primary object of the invention is to provide an adjustable check-wire holder having means for properly tensioning the check-wire as it is stretched across the corn field, the adjustable tensioning means being designed to permit the check-wire to be equally tensioned as it is moved from one position to another for regulating and governing the rows of planted corn.

A further object of the invention resides in the provision of a stake carrying a tube which incloses a spring for providing various tensions on the check-wire.

As a further object of the invention the device is provided with locking dogs which are adapted to register with teeth disposed in position for permitting the tension of the wire to be regulated to any desired tension.

Figure 1 is a vertical longitudinal section through the tensioning device showing the stake in elevation.

Fig. 2 is a vertical section on the line 2—2 of Fig. 1.

Fig. 3 is an end view of the wire holding hook.

Fig. 4 is a fragmentary section on the line 4—4 of Fig. 1.

The stake 1 is provided with a sharpened end 2 for permitting the stake to be driven into the ground at the side of the corn field. For manually forcing the stake into the ground, a foot-plate 3 is provided and extends laterally from a collar 4 slidably mounted upon the rod 1 and secured thereto by a set screw 5. The upper end of the rod 1 is provided with a loop 6 by which the stake may be withdrawn from the ground when desired.

A casing 7, of tubular formation is provided with openings 8 through which is extended the stake 1 and the casing 7 is thereby permitted to slide upwardly or downwardly for adjusting the casing to the desired height. The casing is provided on its

top with a longitudinal slot 9 which extends from the upper end of the casing forwardly to a point adjacent one of the openings 8. Integrally formed with the casing 60 7 at each side of the slot 9, is a plurality of notches 10, the notches on one side of the slot being cut at the reverse angle to the notches on the opposite side thereof. The forward end of the casing is closed by an 65 end wall 11 which is provided with a pair of openings, laterally spaced apart, and through which are extended the rods 12 which are also laterally spaced apart and disposed within the casing. The forward 70 ends of the rods 12 carry a plate 13 to which is secured the check-wire holding hook 14. The bill of the hook is bifurcated to permit the insertion of the check-wire and, when one of the knots in the check-wire is disposed within the hook and the check-wire extended through the bifurcation, any accidental displacement of the wire from the hook will be prevented.

Mounted within the casing, adjacent the 80 rear end thereof, is a sliding bushing 15 to which is secured the ends of the rods 12. Secured to the bushing 15 and extending upwardly through the slot 9 in the casing, is a locking arm 16 to the upper end of 85 which is pivoted the locking dogs 17 and 18, which is adapted to register with the notches 10 on the casing.

Arranged within the casing, and interposed between the stake 1 and the bushing 90 15 is a coiled expansion spring 17, the coils of which surround the rod 12. This spring permits the same tension to be maintained at all times upon the check-wire.

In operating the device, in connection 95 with the planting of a row of corn, the stake will be first driven into the ground at the edge of the corn field, and one of the knots in the check-wire caught into the hook 14. The locking arm 16 will be moved rearwardly to a predetermined distance from the end of the casing and the locking dogs permitted to drop into engagement with the notches thereby holding the hook at a certain distance from the end of the casing. 100 The opposite ends of the check-wire will be fixed in any suitable manner to the opposite edge of the field. This may be accomplished by driving a stake into the ground at the desired point and fixing the end of the 110 check-wire to the stake.

By referring to Fig. 4 of the drawing it

will be noted that the notches in the two series of notches are arranged in staggered relation, that is, the notches at one side of the slot 9 are disposed midway between the notches at the opposite side of the slot 9, so that the pawl 17 is engaged with one of its notches, the pawl 18 will rest midway between two of its notches as shown by Fig. 4 of the drawing. The coil expansion spring presses the pawl 17 into engagement with its notch, while a slight forward movement of the rods 12 is permitted, this movement being limited by the distance the edge of the pawl 18 is disposed from its notch.

15 The locking dog 17 prevents the expansion spring 17' from pulling the hook beyond the desired point while the planter is progressing from one knot to the next. The locking dog 18, in registration with the notches on the opposite side of the slot 9, prevents the check-wire from becoming slackened when the planter strikes one of the knots in the check-wire. Each of the locking dogs are provided with a lifting-

20 wire 19 connected to a ring 20 through the medium of which the locking dogs may be drawn out of engagement with the teeth or notches when moving the locking arm from one point to another.

25

30 I claim:

1. A check-wire holder including a stake, and tensioning means carried by and disposed at right angles to the stake and adapted to be secured to a check-wire, including a pair of locking dogs for holding the check-wire at a pre-determined tension.
2. A check-wire holder including a stake, a casing disposed at right angles to the stake and provided with oppositely disposed apertures through which the stake is extended, said casing being also provided with a plurality of longitudinally arranged notches, tensioning means arranged within the casing and adapted to be secured to a check-wire, said means including a locking element for holding the check-wire at a pre-determined tension provided by said tensioning means.
3. A check-wire holder including a stake, 50 a tubular casing carried by the stake and disposed at right angles thereto, said casing being provided with a longitudinal slot, a plurality of notches provided on the cas-

ing, said notches being arranged in a pair of longitudinal rows on opposite sides of 55 said slot, and tensioning means arranged within the casing and adapted to be connected to a check-wire for permitting a tension to be maintained on the check-wire, and a pair of locking dogs pivotally carried by 60 the tensioning means and adapted to register with said notches.

4. A check-wire holder including a stake, a tubular casing carried by the stake at right angles thereto, said casing being provided 65 with a longitudinal slot and carrying a series of longitudinally arranged notches adjacent the edges of the said slot, a bushing slidably arranged within the casing, and locking means carried by the casing and adapted to 70 register with the said notches.

5. A check-wire holder including a stake, a tubular casing carried by the stake at right angles thereto, said casing being provided 75 with a longitudinal slot and carrying a series of longitudinally arranged notches adjacent the edges of the said slot, a bushing slidably arranged within the casing, locking means carried by the casing and adapted to register with the said notches, means connecting the said bushing with a check-wire 80 for permitting a tension to be maintained on the check-wire, the said locking means adapted to hold the said check-wire at a pre-determined tension.

85 6. A check-wire holder including a stake, a tubular casing carried by the stake and disposed at right angles thereto, a pair of connecting rods disposed within the casing and adapted to connect at their forward 90 ends to a check-wire, an expansion spring disposed within the casing and surrounding said connecting rods, said expansion spring having one end bearing against the said stake, and locking means attached to the opposite ends of the said connecting rods and receiving the opposite end of said expansion spring, said locking means adapted to hold the check-wire at a pre-determined tension.

95 In testimony whereof I affix my signature 100 in presence of two witnesses.

WILLIAM S. PETERSEN.
